Specification for Design.

Patented Apr. 4, 1922.

Application filed September 18, 1920. Serial No. 411,329. Term of patent 3½ years.

To all whom it may concern:

Be it known that I, RALEIGH O. HUMPHREY, a citizen of the United States, residing at Chicago, in the county of Cook and State of Illinois, have invented a new, original, and ornamental Design for an Oil Stove of That Type Adapted to Use Hydrocarbon Fuels, of which the following is a specifica-

tion, reference being had to the accompanying drawing, forming part thereof.

The figure is an elevational view of an oil stove showing my new design.

I claim:

The ornamental design for an oil stove as shown.

RALEIGH O. HUMPHREY.
